UNITED STATES PATENT OFFICE.

CLIFFORD T. BOWEN, OF WELLINGTON, AND ASA C. BOWEN, OF CLEVELAND, OHIO.

LICENSE-PLATE HOLDER.

Application filed February 1, 1923. Serial No. 616,342.

To all whom it may concern:

Be it known that we, CLIFFORD T. BOWEN and ASA C. BOWEN, citizens of the United States, and residents, respectively, of Wellington, in the county of Lorain, State of Ohio, and Cleveland, county of Cuyahoga, State of Ohio, have invented a new and Improved License-Plate Holder, of which the following is a full, clear, and exact description.

This invention relates to improvements in license plate holders, and more particularly to such devices for use in connection with motor vehicles, an object of the invention being to provide an improved construction of holder which is adapted to secure any ordinary size and shape of license plate, supporting the same either at the center or at a point adjacent either end, and which can be conveniently attached to any desired part of an automobile.

A further object is to provide a holder of the character stated, which will embody but few inexpensive parts, which can be assembled and adjusted by any one of average intelligence, and which will most efficiently secure the license plate at the point desired.

A further object is to provide a holder of the character stated, which can be sold at a reasonably low price and yet which will be strong and durable in use.

With these and other objects in view, the invention consists in certain novel features of construction and combinations, and arrangement of parts, as will be more fully hereinafter described and pointed out in the claims.

In the accompanying drawings—

Figure 1 is a view in rear elevation of our improved holder showing the license plate in dotted lines.

Figure 2 is a view similar to Figure 1 but illustrating a modification.

Figure 3 is a view in transverse section on the line 3—3, of Figure 1.

Figure 4 is a fragmentary view in transverse section on the line 4—4, of Figure 3.

1 and 2 represent the clamping members of our improved holder. These members 1 and 2 are preferably stamped or otherwise formed from sheet metal, and have their longitudinal edges bent backward upon the main portion of the members, but spaced slightly from the members constituting holding flanges 3, which project over the front

face of the license plate 4 so that the members constitute jaws of an appreciable length so as to firmly grip the edges of the license plate.

The upper jaw 1 at its central portion is formed with a depending tongue 5 having an integral perforated plate 6 thereon projecting from its lowest edge at right angles thereto. The lower clamping member 2 has an upwardly projecting tongue 7 which is bent at right angles forming a clamping plate 8, which is disposed parallel to the clamping plate 6, and is perforated for the reception of a clamping bolt or screw 9, a nut 10 being positioned on the lower end of the screw or bolt, with the head 11 of the nut or bolt against the upper face of plate 6.

At the outer end of the plate 8 which is integral with tongue 7, a downward integral extension 12 is provided, and this extension 12 is approximately parallel with the tongue 7 and spaced therefrom a distance to accommodate the nut 10, but prevent rotary movement of the nut so that by manipulating the head 11 of the clamping screw, the two clamping members can be readily adjusted relative to the license plate, or removed altogether therefrom.

In Figures 1, 3 and 4, we illustrate an angle bracket 13 as a means for connecting the extension 12 with any suitable support or part of the automobile. This angle bracket 13 is also preferably of sheet metal, its vertical member 14 positioned against the extension 12 and its horizontal member 15 having a perforation 16 therein for the reception of a securing bolt or other device.

A bolt or screw 17 and a nut 18 are utilized to secure the bracket 14 and the extension 12, and to hold these parts against possibility of pivotal movement, they are formed with registering countersunk portions 19. These countersunk portions forming in effect, grooves and webs which prevent pivotal movement, and in order to provide both vertical and horizontal interlocking webs and grooves, we preferably form the countersunk portion of general star shape so that the nut 18 positioned in the center thereof will be held against turning movement, so that by manipulating the head of the bolt or screw the parts can be readily clamped or released.

When an angle bracket, such as shown at 13, is not desirable by reason of the fact that the license plate is to be secured to a hori-

zontal rod plate, or other such support, we provide a bar 20 as a substitute for the bracket 13. This bar 20 is likewise formed with an offset portion 19 and is made with 5 longitudinal slots 21 for any desired securing devices.

It will thus be noted that with our improved clamp, the license plate can be securely held at any point throughout its 10 length, and rigidly secured in such position when properly attached to a vehicle.

Furthermore, the license plate can be easily and quickly inserted and removed, and when in place will also be securely held.

15 It will also be noted that the nuts 10 and 18 are held against turning movement so that by manipulating the heads of the screws or bolts, either by screw driver or wrench, a proper adjustment can be had, and also 20 the supporting parts, either the angle clamp 13 or the bar 20, as the case may be, are securely held against possibility of pivotal movement.

Various slight changes might be made in 25 the general form and arrangement of parts described without departing from our invention, and hence we do not limit ourselves to the precise details set forth, but consider ourselves at liberty to make such changes 30 and alterations as fairly fall within the spirit and scope of the appended claims.

We claim:

1. A license plate holder, comprising a

pair of clamping members, overturned edges on the clamping members receiving 35 the edges of the license plate, tongues on the members at the back of the license plate, plates projecting at right angles from and integral with the tongues, said plates having aligned openings therein, a bolt or screw 40 projected through said openings, a nut on one end of the bolt, an extension on one of said plates and extending in spaced and parallel relation to the tongue carrying the plate and between which and the tongue the 45 said nut is located, whereby the nut is held against turning movement, and a supporting member clamped to the extension and adapted to be secured to a vehicle.

2. A license plate holder, comprising a 50 pair of clamping members, a bolt and nut clamping the members to a license plate, an extension on one of said members, a supporting member, said extension and said supporting member having registering star-shaped countersunk portions adapted to hold the said extension and supporting member against relative pivotal movement, a nut fitting within the countersunk portion of said extension and held by the walls 55 thereof against turning movement, and a screw or bolt projected through the extension and the supporting member and screwed into the nut.

CLIFFORD T. BOWEN.
ASA C. BOWEN.
